OIL RETURN MEANS FOR FLOODED
EVAPORATORSJoseph Askin, Buffalo, N. Y., assignor to Fedders
Manufacturing Company, Inc., Buffalo, N. Y.

Application October 13, 1932, Serial No. 637,607

6 Claims. (Cl. 62—126)

This invention relates to refrigeration evaporators of the flooded type such as are employed in compressor-condenser-expander systems of mechanical refrigeration, and it has particular reference to the provision of means for effecting the copious return of oil from the evaporator to the compressor without concomitant return of liquid refrigerant.

It is well understood in the art that, in the type of refrigeration apparatus referred to, oil tends to accumulate in the evaporator, and some provision must be made for its return to the compressor, together with gasified refrigerant. It is likewise desirable to prevent the return of liquid refrigerant to the compressor, as losses of operating efficiency result if this condition occurs. If the oil is returned too rapidly, however, the tendency to return refrigerant is augmented, while, if too slow an oil return rate is attempted, the refrigerator may become oil logged, and so lessened in its refrigerating capacity. Oil logging may take place in a system which operates satisfactorily under certain conditions, if those conditions be materially changed. For example, it has been noted that a domestic refrigerator operating properly under approximately full capacity may become oil logged when it is subjected to very light duty, as might be the case if a family were absent from the residence during a vacation season.

The present invention provides for the return of oil in such copious quantities as to prevent oil logging from this or any other cause, while limiting the return of refrigerant to a normal amount, and then in the form of gas, and it also provides a wick feed for oil return purposes which exerts a constant effect on the oil in which it is immersed, irrespective of variations in the liquid level in the evaporator. In setting forth the principles of the invention as applied to practice, reference will be made to a type of oil return device in which an open cup is adapted to receive lubricant and refrigerant for return to the compressor through a suction line disposed in the cup, but it will be understood that the invention may be embodied in other forms within the purview of the following claims.

In the drawing, Fig. 1 is a transverse section through an evaporator header containing the invention;

Fig. 2 is a longitudinal section; and,

Fig. 3 is a perspective of a cup shown in Figs.

1 and 2.

The evaporator is illustrated as comprising a cylindrical shell 10 from which depend a plural-

ity of tubes 11, and which is closed at one end by a plate 12 provided with an inlet line 13 and a suction line 14. The inlet line 13 passes through a boss 15, formed on the plate, in which is mounted an inlet valve 16, the opening of which is controlled by a pivoted float member 17, in the form of an open cup or receptacle. A suction tube 18, depending into the cavity of the cup 17, leads to the suction line 14.

The operation is that, as refrigerant evaporates in the cylinder 10 and tubes 11, to produce refrigeration, the liberated gases, together with such lubricant as they may carry, fall into the cup 17 and are returned to the compressor through the suction tube 18. Such evaporation lowers the liquid level in the evaporator, thereby permitting the float 17 to drop, open the valve 16, and admit mixed liquid refrigerant and lubricant to the evaporator to reestablish the liquid level therein. As the oil is lighter than the refrigerant, it floats on the surface thereof, and is carried into the cavity of the float during the evaporating action.

As stated above, a violent evaporating action may cause the injection of large quantities of liquid refrigerant into the cup 17, which is not desired, while a very quiet action may not cause sufficient disturbance to discharge the oil into the cup, thereby leading to oil logging of the system. To avoid both of these defects, this invention provides for guarding the cavity of the cup from the injection of liquid refrigerant, and provides means for the taking up of substantial volumes of the oil floating on the refrigerant surface.

To this end, the cup 17 is covered with a cover plate 21, which is shown as being in the form of a lid having turned under marginal portions 22, adapted to engage outwardly turned flanges 23 formed on the cup itself. A slot 24, guarded by an upwardly turned flange 25, is formed at the rear portion of the lid 21, so that the lid may be slid over the cup and beyond the tube 18. The clearance between the flange 25 and the tube 18 provides an input passage for directing the gases to the tube 18 and it is additionally proportioned to permit the bucket 17 to rise and fall freely with the liquid level, so as not to interfere with the action of the valve 16, but the gap is not wide enough to provide for the free passage of large amounts of liquid refrigerant which may occasionally be splashed over the rear portion of the cup and around the tube 18.

The plate 21 is provided, at a number of points adjacent its margin, with narrow slots or openings 26, in which are disposed wicks 27, dipping at their outer ends into the region of the oil

layer in the evaporator, and terminating at their inner ends within the cavity of the float. These wicks may be made simply by folding fine mesh copper screen, say from eighty to two hundred 5 mesh, on itself a number of times, and then flattening the folds by a hammer blow or the like.

The size of the wicks is of some importance, and is readily ascertainable for any given evaporator. A fine wick, such as one made of two 10 hundred mesh wire, does not feed oil from the supernatant layer into the cup as rapidly as an eighty mesh wick of the same length and width. However, a coarse mesh wick may be so active as to carry into the float an appreciable amount of 15 liquid refrigerant, and hence, in providing for a plurality of wicks, it is understood that mere feeding capacity alone is not contemplated, but the major purpose of using a large number of wicks is to provide for high oil return capacity, without 20 increasing the refrigerant return.

In the present device, it has been found that three or four wicks of one hundred mesh screen serve to return the oil as rapidly as it accumulates, with practically no liquid refrigerant return. 25 Thus, the use of a number of slow feeding wicks is preferred to a single fast feeding wick, since the former arrangement provides an enlarged evaporative surface for the liquid refrigerant which is occasionally carried with the oil.

The length of the exterior leg of the wick is, of course, constant, and its depth of immersion is determined for normal operating conditions by mounting the wick on a floating cup. Since the cup rises and falls with the mixed refrigerant and 30 oil, variations in such level do not affect the depth of immersion, and hence the capillary or drawing power of the wick, as might be the case if the cup 17 were fixed with respect to the shell. 35 Such construction is advantageous in preventing the return of liquid refrigerant through the wicks.

The apertures 26, through which the wicks 27 pass, preferably engage the wicks snugly, so that any liquid refrigerant which spreads out over the 40 surface of the plate 21, and attempts to flow through the apertures, is taken up by the wicks, to be further retarded in its flow as liquid, or to be taken up by the oil in the wicks and so rendered 45 ineffective to cause backfrosting. In operation, 50 gasified refrigerant passes from the vapor space above the liquid levels into the cavity of the cup 17 and thence into the suction tube 18, flowing through the apertures which are always open to it. Liquid refrigerant, which may be splashed 55 on the plate 21, is so impeded in its progress that an opportunity is given to it to evaporate, and hence practically no liquid refrigerant is admitted to the return line. Oil is returned by the 60 wicks, which, due to their nature, take up the oil preferentially to the liquid refrigerant, and at such rate that the oil is returned practically as fast as it collects. Oil may also be returned through the openings in the plate 21, or with the 65 gasified refrigerant, which serves as a carrier for small oil particles.

The wicks 27 may be of such size as to be 70 automatically disengageable from the liquid in the header when the oil is drained therefrom, with the object of preventing the withdrawal of pure liquid refrigerant from the header. This is provided for by the differences in specific 75 gravity of the oil and the refrigerant, wherein normally the relatively light oil floats on the refrigerant in a layer of approximately one half inch, and, inasmuch as it affects the buoyancy

of the float, it also affects the liquid level in the header, which is dependent upon the valve-controlling action of the float. Under these conditions, which may be assumed to be normal, the float is deeply immersed in liquid, and, as a result 5 the wicks enter the oil layer. However, in the absence of or during a substantial depletion of the oil layer, the relatively heavier liquid refrigerant alone affects the buoyancy of the float, which therefore floats more readily, and, through 10 its control of the valve, in effect lowers the liquid level in the header. The wicks under this condition are withdrawn from the liquid until a substantial quantity of oil enters the header.

Under all operating conditions the return or 15 inner legs of the wicks serve an additional purpose to that described in conveying portions of the liquid occasionally splashed on the plate 21 to the interior of the float. Such a portion may form in a film on the plate and engage the top 20 of a wick 27, whereupon it drains slowly into the float. In this case each wick acts as a tortuous return duct wherein the gravitational flow of such liquid portion is sufficiently slow to permit the evaporation of any quantity of included refrigerant.

It will be noted that the cup 17 serves not only to transmit the various media returning to the compressor, but also serves to control the level of the refrigerant. This arrangement, broadly, is 30 not my invention, except as it has been modified and improved herein, and it will therefore be understood that I contemplate the application of the principles of the invention in forms in which such valve control is not included, and that various other modifications may be resorted to as 35 may suggest themselves to those skilled in the art.

I claim:

1. In a refrigerating apparatus comprising an evaporator having inlet means for admitting lubricant and refrigerant for separation by gravity therein, lubricant return means comprising a closed cup in the evaporator having a top portion extending above the liquid, said top portion having an aperture therein, a wick entering the cup through the aperture of the top portion thereof and having a portion extending into the lubricant, said top portion being adapted to receive deposits of liquid to form a film thereon for slow drainage into the cup through the wick, and an outlet conduit extending from the cavity of the cup to a portion exterior of the evaporator.

2. In a refrigerating apparatus comprising an evaporator having inlet means for admitting lubricant and refrigerant for separation by gravity therein, lubricant return means comprising a cup therein having an opening in its top, said top being above the liquid in the evaporator, means closing said opening, said means comprising a labyrinth structure adapted to gravitationally convey lubricant into said cup to permit evaporation of refrigerant carried with the lubricant during transit, and an outlet conduit entering the cavity of the cup and extending to a point exterior of the evaporator.

3. In a refrigerating apparatus comprising an evaporator having an inlet for admitting lubricant and refrigerant for separation by gravity therein, a control valve for said inlet, lubricant return means comprising an open float positioned within the evaporator for operating said valve, an outlet conduit extending into the float, a cover for said float, passage means in the cover to admit gas to the outlet conduit, and means on the float

for conducting lubricant from the evaporator to the interior of the float.

4. In a refrigerating apparatus comprising an evaporator having an inlet for admitting lubricant and refrigerant for separation by gravity therein, a control valve for said inlet, lubricant return means comprising an open float positioned within the evaporator for operating said valve, an outlet conduit extending into the float, a cover 5 for said float, passage means in the cover to admit gas to the outlet conduit, and wick means extending into the float and having a portion entering the lubricant, said wick means being maintained in the lubricant by the buoying movement of the 10 float.

5. In a refrigerating apparatus comprising an evaporator having an inlet for admitting lubricant and refrigerant for separation by gravity therein, a control valve for said inlet, lubricant 15 return means comprising an open float positioned within the evaporator for operating said valve,

an outlet conduit extending into the float, a cover for said float, passage means in the cover to admit gas to the outlet conduit, cooperating flange means on the float and cover for retaining the cover in assembled relation, and means on the 5 float for conducting lubricant from the evaporator to the interior of the float.

6. In a refrigerating apparatus comprising an evaporator provided with means for admitting refrigerant and lubricant admixed therewith, an 10 open float for controlling the liquid admission means, an outlet conduit extending into the cavity of the float, lubricant return means comprising a cover for the float, and means for conveying liquid deposited on the cover to the interior of the 15 float, comprising a labyrinth structure entering the float through the cover and adapted to slowly convey lubricant into said cup to permit the evaporation of refrigerant carried therewith during transit.

JOSEPH ASKIN.
